Patented Nov. 27, 1923.

UNITED STATES PATENT OFFICE.

CLARENCE P. PETERSON, OF BROOKLYN, NEW YORK.

HOUSE NUMBER AND STEP ILLUMINATOR.

Application filed May 8, 1923. Serial No. 637,534.

To all whom it may concern:

Be it known that I, CLARENCE P. PETERSON, a citizen of the United States, and a resident of the city of New York, borough of Brooklyn, in the county of Kings and State of New York, have invented a new and Improved House Number and Step Illuminator, of which the following is a full, clear, and exact description.

10 This invention has relation to illuminated signs and has particular reference to a combined house number and step illuminator.

The outstanding object of the present invention resides in the provision of means for 15 effectually displaying the number of a house after dark, and which means at the same time serve to properly illuminate the step or steps in order to preclude accidents due to stumbling while ascending or descending the 20 same.

As a further object the invention contemplates a housing number and step illuminator which is extremely simple in its construction, inexpensive to manufacture and 25 produce and which is readily applicable to the riser of a step.

With the above recited and other objects in view, the invention resides in the novel construction set forth in the application 30 specification, particularly pointed out in the appended claim and illustrated in the accompanying drawing, it being understood that the right is reserved to embodiments other than those actually illustrated herein 35 to the full extent indicated by the general meaning of the terms in which the claim is expressed.

In the drawing—

Figure 1 is a perspective view of the number and step illuminator in its applied position.

Fig. 2 is an enlarged front view of the same removed.

Fig. 3 is a horizontal sectional view taken 45 approximately on the line 3—3 of Fig. 2.

Referring to the drawing by characters of reference the combined number and step illuminator consists of a box-like housing or casing 10 which is provided adjacent its 50 front open end with laterally projecting apertured ears 11 through which screws, nails, or other fastening elements 12 are

adapted to be driven and anchored into the riser 13 of a step. The riser is cut away as at 14 to provide an opening for snugly receiving the casing 10. The open front end is adapted to be closed by a door 15 which is hinged thereto as at 16 and is maintained in closed condition by a suitable latch 17. The door is in the nature of a rectangular frame 55 having vertical spaced front and rear guide grooves 18 and 19 in its side rails 20, the former adapted to receive a transparent panel 21 upon which the housing number digits 22 are suitably inscribed. The rear 60 grooves 19 are designed to receive a colored transpicuous panel 23 which serves to mask from view the interior of the casing 10 when the lamp 24 is lighted. The panel 23 further serves as means for protecting the 65 front panel 21 from the heat of the lamp whereby to prevent said heat from effecting the numerals or digits of the house number. In practice the rays of the lamp when lighted 70 effectually illuminate and display the house number, while at the same time the uppermost step is properly illuminated to preclude accidental stumbling either in ascending or descending the steps. It is of course understood that the hinged door 15 permits 75 of the gaining of access to the interior of the casing 10 for the purpose of replacing a burnt out lamp or renewing either of the panels 21 or 23, if broken.

I claim:

85 A combined house number and step illuminating device comprising a casing adapted to be fitted in the opening of a riser of a front step, a door hingedly mounted on the open front end of the housing, a transpicuous panel removably carried by said door having inscribed thereon digits representing the number of said house, illuminating means within the housing adapted to cast light rays 90 through the panel for displaying the house number and simultaneously illuminating the step, and a colored transpicuous panel mounted in spaced relation in rear of the first panel for protecting said first panel from the heat of the illuminating means and 95 for masking from view the interior of the casing.

CLARENCE P. PETERSON.
